UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

MECHANISM FOR TILTING ROAD-GRADE SCRAPERS OR MOLDBOARDS.

1,318,473.

Specification of Letters Patent.

Patented Oct. 14, 1919.

Application filed May 24, 1919. Serial No. 299,417.

To all whom it may concern:

Be it known that I, FRANKLIN E. ARNDT, a citizen of the United States, residing at Galion, in the county of Crawford and State of Ohio, have invented certain new and useful Improvements in Mechanism for Tilting Road-Grader Scrapers or Moldboards, of which the following is a specification.

10 This invention relates to road graders of that type wherein a transversely extending scraper or mold board is used suspended from the frame of the machine and shiftable into different angles with relation to the line of draft, and particularly to means for pivotally supporting the scraping blade or mold board and for adjusting the scraper or mold board, and for tilting the scraper or mold board into different angles with relation to the road surface and holding it in its tilted or adjusted position.

25 In the successful operation of road graders, particularly large road graders, it is very necessary to be able to change the angle of the mold board or scraper so that the scraper shall either stand approximately perpendicular to the work and exert a scraping action as distinguished from a cutting action, or shall be disposed at less than 30 a right angle to the work so that it may cut in under the work and give a better cutting slant to the blade.

35 The general object of this invention is to provide improved means for adjusting the angle of the blade to the work and holding it in its adjusted position.

40 And a further object is to provide means for this purpose so constructed that a single operating shaft will shift all portions of the blade at the same time, thus permitting the blade to be adjusted by one operator with one actuation, doing away with the necessity of securing the tilting of the blade by the use of a plurality of adjusting devices, each requiring to be separately adjusted.

45 A further object is to provide a construction of this character which will hold the blade firmly against the strains to which it is submitted.

50 Another object is to provide a unitary adjusting and locking means which, when it is adjusted, will hold the blade against further tilting movement in either direction.

A further object is to provide a tilting or adjusting mechanism which is so housed as to prevent dust, mud, or other foreign matter from having access to the adjusting mechanism and clogging it, and which will prevent the parts from becoming rusted.

A further object is to provide adjusting means so constructed that the adjustment of the blade cannot be changed by unauthorized parties or mischievously.

65 Other objects will appear in the course of the following description.

My invention is illustrated in the accompanying drawings, wherein:—

Figure 1 is a fragmentary side elevation 70 of a conventional type of road grader with my improvement applied thereto, the circle 14 being in section;

Fig. 2 is a side elevation of the scraper and its adjustable supporting means, the beam 15^a being in section; and

Fig. 3 is a fragmentary rear elevation of the scraper supporting means, the beam 15^a being in section.

75 In the accompanying drawings I have illustrated my invention as applied to a certain form or type of grading machine designed for very heavy work. I have illustrated such a machine in Fig. 1, but obviously the invention might be applied to other forms of grader. Inasmuch as the form of grading machine illustrated in Fig. 1 is well known, it is only necessary to say that it comprises a supporting frame consisting of longitudinally extending, upwardly bowed beams 10 operatively mounted upon the front wheels 11, and the rear wheels 12, the rear wheels being the steering wheels and the forward wheels supporting the rearwardly extending floating beams

95 13, carrying the usual "circle" 14, which may be a complete circle or only part of a circle, and carries the rotatably mounted supporting member 15 thereon, which is rotatably adjusted by means of a pinion 16 mounted 100 upon an upwardly and rearwardly extending shaft 17 having a crank handle at its upper end.

105 Means is provided for vertically adjusting the floating beams 13 independently of each other to secure the proper lateral tilt or inclination where necessary. Of course, the machine is provided with steering mechanism and draft mechanism, but inasmuch as these machines are well known, it is not 110

deemed necessary to describe these details of construction.

Attached to the rotatable supporting member 15 and depending therefrom are a plurality of knees or brackets 18, these brackets being curved downward and rearward and then forward and downward and decreasing in depth toward their lower ends. Disposed in front of these brackets 5 is the scraper or mold board 19 which may be of any suitable form, but is shown as downwardly and forwardly curved, a cutting blade 19^a being attached to the lower edge of the mold board. Bolted or otherwise 10 attached to the lower margin of the mold board or scraper upon its rear face is a longitudinally extending angular bracket 20 having thereon upwardly and rearwardly extending, perforated ears 21, which are 15 pivoted to the lower ends of the brackets 18. These brackets 18 at their upper ends are angularly bent and riveted, bolted, or otherwise attached to the transversely extending member 15^a which forms part of the rotatable element 15.

Extending through and supported in the brackets 18 is a transverse shaft 22 which, at a plurality of points, is provided with crank arms 23, preferably arranged in pairs.

30 At intervals upon the upper portion of the rear face of the scraper or mold board 19 are disposed angular brackets 24, and pivotally connected to these brackets are the links 25 which, in turn, are pivotally connected 35 to the pairs of crank arms 23. It will thus be obvious that when the shaft 22 which, as before stated, is mounted in suitable bearings on the brackets 18, is oscillated in one direction or the other, the mold board will 40 be tilted from a position where it is approximately perpendicular to the surface of the roadway, to a position where it is disposed at less than a right angle to the surface of the roadway.

45 It will be noted from Fig. 2 that the mold board 19 extends slightly above the channel bar 15^a so that this channel bar acts as a stop limiting the rearward movement of the upper portion of the mold board, but I do 50 not wish to be limited to this or to the exact position of this stop. The mold board 19 and the blade 19^a have such a curvature, however, that when the mold board is brought back against this stop formed by 55 the end beam of the channel 15^a, the blade will exert a shearing cut, but when the shaft 22 is turned so as to force the upper portion of the mold board outward to its full extent, the blade 19^a will be turned to a position perpendicular to the road surface and will exert 60 a purely scraping action.

For the purpose of rotating the shaft 22 and thereby adjusting the angle of inclination of the scraper or mold board, I mount 65 upon the shaft 22 a worm wheel 26, which is

keyed to this shaft and which is engaged by a horizontally disposed worm 27 having a shaft 28 which extends rearward and terminates in a polygonal head whereby a wrench or handle may be applied to thereby 70 rotate the shaft 28. This worm wheel and worm are preferably disposed within a housing formed in two sections, one of said sections 29 having a circular portion covering the worm wheel and a portion covering the 75 worm, and having bearings for the support of the worm shaft and having flanges adapted to be bolted or otherwise attached to the channelled member 15^a, this section being formed with a circumferential flange 30 80 having perforated ears. The opposite section 31 simply consists of a plate fitting upon the circumferential wall 30 or the other section of the housing and also formed with perforated ears for the passage of 85 screws whereby the two sections may be engaged with each other. Thus, the worm and worm gear are entirely housed and protected from dust, dirt, mud, and other 90 foreign matter, and these parts may, if desired, run in oil, though, of course, there is no particular necessity for this under ordinary circumstances.

When it is desired to adjust the mold board, a preferably crank-shaped wrench is 95 applied to the polygonal head of the shaft 28 and the shaft rotated in one direction or the other. I do not wish to be limited to having the worm shaft disposed in a horizontal position, as it is obvious that it may 100 be disposed in any other suitable position, either vertically or horizontally, or between the two. Neither do I wish to be limited to the use of a worm gear shaft designed for engagement by a detachable wrench, as it is 105 obvious that any suitable means may be permanently mounted upon this shaft whereby it may be rotated. By providing it with a polygonal head, however, the wrench may be detached after the mold board has been 110 adjusted and there will be no chance whatever for the adjustment of the mold board to be changed with the use of a light wrench for the purpose. This prevents careless or 115 mischievous persons from meddling with the adjustment of the mold board.

It will, of course, be understood that by providing a worm wheel and a worm engaging it, that the worm will hold the worm wheel from any rotative movement, and thus this worm gear acts to hold the shaft in adjusted position and, therefore, the scraper or mold board in its adjusted position against the strains to which it is subjected.

While I have illustrated certain details of construction and arrangement of parts which I have found to be of practical value in use, yet I do not wish to be limited to these details or arrangements, as it is ob- 130

vious that many changes might be made therein without departing from the spirit of the invention as set forth in the appended claims.

5 I claim:—

1. In a machine of the character described, a supporting element having depending brackets, a scraper pivotally connected adjacent its lower and cutting edge to said

10 brackets for tilting movement, a transverse shaft supported in said brackets, a plurality of operative connections between the shaft and the upper portion of the scraper whereby the upper portion of the scraper may be

15 shifted toward or from the brackets upon an oscillation of the shaft, a worm wheel mounted upon the shaft, and a manually controllable worm engaging said worm wheel whereby the inclination of the scraper

20 may be adjusted and the scraper held in its adjusted positions.

2. In a machine of the character described, a supporting element having depending brackets, a scraper pivotally connected adjacent its lower and cutting edge to said brackets for tilting movement, a transverse shaft supported in said brackets, a plurality of operative connections between the shaft and the upper portion of the scraper where-

25 by the upper portion of the scraper may be shifted toward or from the brackets upon an oscillation of the shaft, a worm wheel mounted upon the shaft, a manually controllable worm engaging said worm wheel

30 whereby the inclination of the scraper may be adjusted and the scraper held in its adjusted positions, and a housing inclosing the worm wheel and worm and operatively mounted upon the supporting member, the

35 worm shaft projecting through said housing.

3. In a machine of the character described, a supporting element having depending brackets, a scraper pivotally connected adjacent its lower and cutting edge to said brackets for tilting movement, a transverse shaft supported in said brackets, a plurality of operative connections between the shaft and the upper portion of the scraper

whereby the upper portion of the scraper 50 may be shifted toward or from the brackets upon an oscillation of the shaft, a worm wheel mounted upon the shaft, and a manually controllable worm engaging said worm wheel whereby the inclination of the scraper 55 may be adjusted and the scraper held in its adjusted positions, the worm shaft having a many-sided end whereby it may be rotated.

4. A road grader including a wheeled supporting frame, a supporting member carried by the frame and mounted for rotation in an approximately horizontal plane, brackets operatively connected to the supporting member and extending downward and forward therefrom, a scraper having ears projecting from its rear face and pivotally connected to the extremities of the brackets, a shaft passing through said brackets, a plurality of links pivotally connected to the upper portion of the scraper, means operatively connecting the links to the shaft to cause a reciprocation of the links upon a rotation of the shaft to thereby tilt the scraper, and a single means for manually 75 oscillating the shaft, said means acting to hold it in its adjusted position.

5. A road grader including a wheeled supporting frame, a supporting member carried by the frame and mounted for rotation 80 in an approximately horizontal plane, brackets operatively connected to the supporting member and extending downward and forward therefrom, a scraper having ears projecting from its rear face and pivotally connected to the extremities of the brackets, a shaft passing through said brackets, a plurality of links pivotally connected to the upper portion of the scraper, means operatively connecting the links to the shaft to 90 cause a reciprocation of the links upon a rotation of the shaft to thereby tilt the scraper, a worm wheel mounted upon the shaft, and a manually operable worm engaging the worm wheel whereby the shaft may be oscillated and held in its adjusted position.

In testimony whereof I affix my signature.
FRANKLIN E. ARNDT.
